IMAGE CONVERTER TUBE

Albert Rose, East Orange, N. J., assignor to Radio Corporation of America, a corporation of Delaware

Application August 31, 1939, Serial No. 292,799

6 Claims. (Cl. 250—150)

My invention relates to light sensitive devices and more particularly to electron-optical converter tubes capable of high image amplification.

In a conventional image converter tube the electron currents produced by light on a photocathode are often too weak to produce sufficient fluorescence on the viewing screen. While it has been proposed to interpose between the photocathode and the fluorescent screen one or a number of mesh-like secondary electron emitters for image multiplication purposes, such arrangements have not been altogether satisfactory because of the difficulty of obtaining a satisfactory mesh-like electrode having uniform secondary electron emission over its entire surface and because of the decrease in resolution obtainable with such mesh-like electrodes.

It is an object of my invention to provide an electron-optical image converter tube wherein the intensity of the converted image may be greatly increased. It is another object of my invention to increase the intensity of a converted image without introducing distortional effects such as nonuniformity of the converted image. It is a further object of my invention to provide a tube of the type described wherein uniform amplification of the converted image may be obtained, and it is a still further object to provide a tube of the electron multiplier type wherein the intensity of the multiplying effect may be increased beyond that obtainable with the type using perforated secondary electron emitters. In accordance with my invention I provide an image converter tube having imperforate planar secondary electron emitters arranged to receive a focused electron image from a photocathode along one path and to deliver a focused secondary electron image to a further secondary emitter or to a fluorescent screen along a different path, the electrons flowing along the two paths being acted upon by the same focusing and deflection means. These and other objects, features and advantages of my invention will become apparent from the following description taken in connection with the accompanying drawing in which:

Fig. 1 is a perspective view of a tube made in accordance with my invention and Fig. 2 is a plan view showing a modification of my invention.

Referring to Fig. 1, the envelope 1, which is preferably cylindrical, is closed at one end by an optically transparent window 2 and encloses a substantially transparent photocathode 3 adjacent the window 2 and a secondary electron emitting electrode 4 opposite the photocathode.

The transparent photocathode 3 is preferably placed to one side of the longitudinal axis of the envelope 1 which preferably passes through the center of the secondary emitting electrode 4. On the other side of the longitudinal axis from the photocathode 3 and parallel with the photocathode, I provide an electron receiving target such as the fluorescent target 5 which faces the secondary electron emitter 4.

In accordance with my invention I provide means to focus the electrons liberated from the photocathode 3 upon the secondary electron emitter 4 and to simultaneously focus secondary electrons emitted by the secondary emitter 4 upon the target 5, said means comprising as shown in Fig. 1 a magnetic coil 6 which surrounds the envelope 1 and extends over the space separating the photocathode 3 and target 5 from the secondary emitter 4. The coil 6 is positioned to generate a magnetic field having lines of force substantially perpendicular to the electrode structures 3, 4 and 5, the lines of force extending throughout substantially the entire length of the envelope 1. Furthermore, I provide means to direct the electrons from the photocathode 3 upon the secondary emitter 4 and to simultaneously direct secondary electrons emitted by the emitter 4 upon the target 5, such as a pair of plates 7 and 8 having a separation at least equal to the width of the photocathode 3 and target 5.

In operation an optical image such as represented by the arrow 9 is projected upon the photocathode 3 through the lens system 10 to liberate electron streams from various areas of the photocathode 3 in accordance with the light and shade areas of the optical image. The electron streams emitted from the photocathode are focused by the magnetic field generated by the coil 6 and follow substantially straight paths while under the sole influence of this field. The plates 7 and 8 are energized from a source of constant D. C. potential to generate an electrostatic field which deflects the electrons from the photocathode 3 so that they impinge upon the secondary electron emitter 4 even though it is offset from the photocathode 3. The secondary electron emitter 4 is maintained positive with respect to the photocathode 3 by a battery or other direct current potential source 11 but negative with respect to the target 5, the target 5 being maintained highly positive with respect to the secondary emitter 4 preferably by the same battery or potential source 11. The plates 7 and 8 may be operated at the desired constant potential by a separate battery or potential source 12,

50
55

the electrical midpoint of which is preferably maintained at the same positive potential as the target 5.

Referring again to Fig. 1, the electrons liberated from the photocathode 3 follow paths such as represented by the path A—B while the electrons are under the sole influence of the magnetic field. From points B to C the electrons are deflected by an amount depending upon the potential difference applied to the two plates 7 and 8 and the strength of the magnetic field, this deflection preferably being equivalent to the distance that the center of the photocathode 3 is offset from the center of the secondary emitter 4. The electrons leave the electrostatic field between the plates 7 and 8 such as at the point C and travel along substantially straight paths to the secondary electron emitter 4 such as along the path C—D, whereupon secondary electrons are emitted in quantities which bear a linear relation to the quantities of electrons from the photocathode. These secondary electrons flow along a path such as represented by the path D—E, approximately the same path as C—D, since over this region the magnetic field generated by the coil 6 constrains the electrons to flow along the lines of force of this field. At the point E, however, the secondary electrons diverge from the path followed by the photo-electrons from the photocathode 3 because of the electrostatic field between the plates 7 and 8 and are therefore directed such as along the path E—F and thence along the path F—G to the target electrode 5. Since the same plates 7 and 35 8 deflect electrons from the photocathode 3 to the emitter 4 and also deflect the secondary electrons from the emitter to the target 5, it is desirable to arrange the emitter 4 symmetrically with respect to the photocathode 3 and target 5. Thus, as shown in Figure 1, it is desirable to provide the center of the secondary electron emitting area of the emitter 4 opposite a point in the plane of the photocathode and target and midway between the centers of the electron emitting and electron receiving areas of the photocathode and target.

It will be obvious from the above that since the electrons from the photocathode 3 do not have to pass through the secondary emitter 4 to reach the target, an imperforate secondary emitting electrode may be used, and I therefore prefer to provide this electrode in the form of a sheet of metal having high secondary electron emitting properties. The metal sheet may, however, be treated to obtain high secondary electron emitting properties. Thus, if the metal is of silver, its surface may be oxidized and treated with caesium during the sensitization process of the cathode 3, as is well known in the art.

While I have disclosed the target 5 as of the fluorescent type provided by a semi-transparent film of metal with a fluorescent coating, it is obvious that when the target 5 is to be viewed directly, the metal sheet need not be of the semi-transparent type.

Referring to Fig. 2 which shows a modification of the structure shown in Fig. 1 and wherein similar parts are similarly referenced, I provide a photocathode 3, an oppositely disposed but offset secondary electron emitter 4 and a second secondary electron emitter 20 which is similarly positioned as the target 5 of the construction shown in Fig. 1. The final target electrode 21 is placed at the same end of the tube as the secondary emitter 4 but offset therefrom. All of the elec-

trodes 3, 4, 20 and 21 are preferably parallel to one another, the electrodes 3 and 20 being in the same plane and the electrodes 4 and 20 likewise being in the same plane but in the opposite end of the envelope.

The operation of the device shown in Fig. 2 is similar to that of Fig. 1 except that two stages of secondary electron emission are obtained without the necessity of using secondary electron emitting electrodes of the perforated type. The modification of my invention shown in Fig. 2 requires an envelope 1 having a somewhat larger diameter than that shown in Fig. 1 for an equivalent size of the photocathode 3, but offers the additional advantage that the converted image 15 appearing on the target 21 is viewed from the opposite end of the tube and the observer is removed from the line of sight between the photocathode 3 and the object which it is desired to observe. The secondary emitter 20 may be maintained at the same potential with respect to the emitter 4 and photocathode 3 as was the target 5 as explained in connection with Fig. 1, and the target 21 may be maintained at a still higher positive potential in order to obtain increased light 25 output on the fluorescent coating of the target.

While I do not wish to be limited to any particular theory to explain the operation of my device, it is believed that the electrons, when subjected to the electrostatic field between the plates 30 7 and 8 and simultaneously subjected to the magnetic field generated by the coil 6, are deflected in planes parallel with the plates. The electrons acquire transverse velocity from the plates 7 and 8 substantially all of which is lost by the electrons when emerging from between the plates, so that the spacial relationship of the electrons is not destroyed. The electrons impinging on the secondary emitter 4 therefore have substantially the same relative spacial relationship as when 35 the electrons were emitted by the photocathode 3, and are received on the secondary emitter over areas corresponding to the areas from which they were emitted. It is thus possible with the use of my device to obtain a greatly amplified flow of 45 electrons wherein the density of elemental areas normal to the flow retains the same relationship irrespective of subsequent secondary electron amplification. The device is therefore suitable for use as an image converter where it is desired 50 to have the converted image correspond to the original optical image.

My improved tube is particularly adapted to image conversion where it is desired to intensify an optical image by forming an intense electron 55 image and projecting the electron image on a target such as a fluorescent screen to produce the intensified optical image. It will be appreciated, however, that my tube is also adapted for use as an electron multiplying device. The term image 60 converter tube is therefore definitive of a tube of the type described and is not limited to a tube which converts an optical image into an intensified image on the target but the term may apply to describe a tube wherein the primary purpose is electron multiplication.

While I have indicated the preferred embodiments of my invention and have indicated the specific application as directed to image converter tubes having a target electrode of the fluorescent 70 type, it will be apparent that my invention is by no means limited to the purpose indicated, to the exact forms illustrated, or to its use in tubes incorporating targets of the luminescent type, but that many variations may be made in the partic- 75

ular structure used such as by replacing the fluorescent target with target electrodes of the mosaic type, without departing from the scope of the invention as set forth in the appended claims.

What I claim as new is:

5. 1. An image converter tube including an envelope, a photocathode and a target adjacent one end of the envelope, a secondary electron emitter adjacent the opposite end of the envelope and facing said photocathode and target, means to generate a magnetic field having parallel lines of force intercepting said photocathode, said emitter and said target normal to their surfaces and extending along the axial distance separating said photocathode and target from said secondary electron emitter and a pair of plates wholly removed from the direct paths between said photocathode, said emitter and said target adapted to be maintained at fixed direct current potentials, one on either side of the space separating said photocathode and target from said secondary electron emitter the plane of said plates being normal to the planes of said photocathode, said emitter and said target.
10. 2. An image converter tube having a photocathode, an oppositely disposed secondary electron emitting electrode facing said photocathode, the center of said secondary electron emitting electrode being displaced from a point directly opposite the center of said photocathode, a target adjacent the photocathode to receive electrons from said secondary electron emitting electrode, magnetic coil means extending over and encircling the space separating said photocathode and said target from said secondary electron emitting electrode to generate a magnetic field having lines of force substantially perpendicular to the said photocathode, target and secondary electron emitting electrode and a pair of plates, one on either side of the space separating said photocathode and said target from said secondary electron emitting electrode, the planes of said plates being normal to said photocathode, said target and said secondary electron emitting electrode to direct electrons emitted from areas on said photocathode to corresponding areas on said secondary electron emitting electrode and to simultaneously direct secondary electrons emitted from areas on said secondary electron emitting electrode to corresponding areas on said target.
15. 3. An image converter tube having an evacuated envelope, a photocathode and a luminescent target electrode adjacent one end of said envelope, the surface of said photocathode being parallel with the surface of said target, an imperforate secondary electron emitter adjacent the opposite end of the envelope and facing said photocathode and target and in a plane substantially parallel with said photocathode and target, a magnetic field generating coil extending at least over the space separating said photocathode and target from said secondary electron emitter to generate a magnetic field having lines of force substantially perpendicular to said photocathode, target and secondary electron emitter and a pair of plates on opposite sides of the space separating the said photocathode and target from said secondary electron emitter to direct electrons from said photocathode to said secondary electron emitter and from said secondary electron emitter to said target when a potential difference is applied to said plates.
20. 4. An image converter tube having an envelope, a photocathode adjacent one end of said
- envelope, a secondary electron emitter adjacent the opposite end of said envelope facing said photocathode, the center of said electron emitter being displaced from the center of said photocathode, a luminescent target adjacent said photocathode and facing said secondary electron emitter and displaced therefrom by an amount equal to the displacement of said secondary emitter from said photocathode, a magnetic field generating coil surrounding said envelope and extending over the space separating said photocathode and said luminescent target from said secondary electron emitter to generate a magnetic field having lines of force substantially normal to the surfaces of said photocathode, secondary emitter and target and a pair of electrostatic deflection plates to direct electrons liberated from said photocathode to said secondary emitter and to direct secondary electrons from said secondary emitter to said target when a constant direct current potential difference is applied to said pair of plates.
25. 5. An image converted tube having an envelope, a set of separated parallel electrodes including a photocathode adjacent one end of said envelope, a second set of separated electron receiving electrodes adjacent the opposite end of the envelope and facing said first set of electrodes, said second set of electrodes being positioned in planes substantially parallel to said first set of electrodes, each of the electrodes of said second set being positioned to receive electrons from an electrode of the first-mentioned set, means comprising an elongated magnetic coil extending over the space separating said sets of electrodes, the longitudinal axis of said coil being perpendicular to said set of parallel electrodes to generate a magnetic field having lines of force extending along parallel paths from one set of electrodes to the other set and a pair of plates substantially perpendicular to the plates of said sets of electrodes, the said plates being on opposite sides of the path between said sets of electrodes to direct the electrons progressively from an electrode of one set to an electrode of the other set.
30. 6. An image converter tube including an elongated evacuated envelope, a magnetic coil surrounding said envelope to generate a magnetic field having lines of force parallel with the longitudinal axis of said envelope, a photocathode having an electron emitting area and a target electrode having an electron receiving area disposed side by side in a plane perpendicular to the magnetic lines of force generated by said coil so as to be traversed by different portions of said magnetic field, a secondary electron emitter having a secondary electron emitting area oppositely disposed from, facing and so located with respect to said photocathode and said target that the center of the secondary electron emitting area of said emitter intercepts a line perpendicular to the plane of said photocathode and said target, cutting said plane midway between the centers of the electron emitting and electron receiving areas of said photocathode and said target, and a pair of plates parallel with the lines of force of said magnetic field, one on either side of the space separating said photocathode and said target from said emitter to direct electrons from said photocathode to said emitter and to simultaneously direct secondary electrons from said emitter to said target.

ALBERT ROSE.
